UNITED STATES PATENT OFFICE.

MILTON M. BAKER, OF SAN FRANCISCO, CALIFORNIA, ASSIGNOR TO THE
SUNSHINE WATER HEATER CO., OF SAME PLACE.

SOLAR OVEN AND COOKER.

SPECIFICATION forming part of Letters Patent No. 681,095, dated August 20, 1901.

Application filed August 27, 1900. Serial No. 28,223. (No model.)

To all whom it may concern:

Be it known that I, MILTON M. BAKER, a subject of the Queen of Great Britain, residing at San Francisco, in the county of San Francisco and State of California, have invented certain new and useful Improvements in Solar Ovens and Cookers, of which the following is a specification.

My invention relates to improvements in solar ovens and cookers, the object of my invention being to provide a device by means of which the rays of the sun may be utilized for furnishing the heat necessary for baking or cooking.

My invention therefore resides in the novel construction, combination, and arrangement of parts for the above ends hereinafter fully specified, and particularly pointed out in the claims.

In the accompanying drawings, Figure 1 is a perspective view of an oven and cooker and means for directing heat thereto. Fig. 1^x is a vertical section of one of the mirrors. Fig. 2 is an end elevation of the oven. Fig. 3 is a cross-section thereof. Fig. 4 is a longitudinal section thereof. Fig. 5 is a perspective of a modified form of the device, showing the same adjustable for the varying positions of the sun. Fig. 6 is a longitudinal central vertical section of the cooker proper in this modification. Fig. 7 is a cross-section on the line B B of Fig. 6, and Fig. 8 is a cross-section on the line C C of Fig. 6.

Referring to the drawings, 1 represents an oven supported on pedestals 2, and 3 represents mirrors arranged opposite to the rear side of said oven. Said pedestals and mirrors are mounted on a platform 50 on rollers 51. This permits the cooker and mirrors to be shifted to face the sun according to the time of day at which it is desired to do cooking or baking. Each mirror 3 is pivotally mounted on a standard 4, jointed at its lower end, as at 5, upon the platform 50 to swing to or from the oven and having a brace 6 hooked into one of a series of eyes 7 to adjustably support the standard in any desired position. The mirrors are pivotally mounted on the standards as axis by means of staples 8, which fit snugly around said standards and enable the mirrors to be set at any angle thereon to direct the solar rays to the oven.

The baking-chamber 9 is rectangular in form, having its sides arranged obliquely to the horizon, and the shelves 10 of said chamber are therefore arranged obliquely to said sides, as clearly shown in Fig. 4. Around the baking-chamber is an air-space 11, extending between the wall 12 of said baking-chamber, and the wall 13 extending outside of and parallel to said wall 12. Around the wall 13 is a packing 14, of a non-conductor of heat, such as a padding of felted wool or dry seaweed, said space being closed by a wall 15. Around said wall 15 is a packing 16 of any cheap non-conducting material, such as sawdust, ashes, or charcoal, ashes being preferred on account of the cheapness. Around said packing is an outer wall 17.

The above is the construction of the whole of three of the six sides of the oven and also of part of each of the other three sides. Two of these latter, the side facing the mirrors and the other upper side, are arranged to permit the rays of the sun indirect and direct to pass therethrough to heat the oven, and for this purpose there is provided on each of said sides a frame 18, having secured therein two sheets of glass 19 20 with an air-space 21 therebetween. Between the inner sheet 20 and the oven is a space forming part of the general air-space around the oven; but in said space in front of the oven, but separated from said oven and sheet by an air-space, is a baffle-plate 22, of metal, which protects the wall of the oven from the rays of the sun.

The door of the oven is hinged at one of its lower edges, as shown at 25, and is closed by a latch 26 at one of its upper sides. Said door is constructed with three sheets of metal 32 33 35, having therebetween an inner packing 34 of felted wool or the like and an outer packing of ashes 36 or the like in the same manner as the remainder of the oven. The edges of the door and of the opening into which it shuts are lined with felt 27, so as to form a tight-fitting joint to prevent the escape of air. The door is provided with a pyrometer, the disk of which is shown at 28.

For the purpose of frying or broiling there is provided a plate 40, extending over the topmost ridge 41 of the oven horizontally. The space between said plate and the oven proper is closed by walls 46, which also serve to sup-

port the plate. Said plate is connected with the interior of the oven by two conduits 42, which at their lower ends communicate with the air-chamber 11. The under side of said plate 40 is thereby brought to a very high temperature. When it is desired to concentrate the heat at one end of the plate 40, the other end can be cut off from the heat by means of a shutter 44, operated by a handle 45, there being one such shutter for each of the conduits 42.

In the modification of the invention shown in Figs. 5, 6, 7, and 8 the cooker proper may be adjusted for the varying altitude of the sun, and for this purpose the oven proper is constructed with a semicylindrical rear portion and has formed on its rear portion circular ribs 52, which move in the circular guides or bearings 53 of pedestals 54. This gives a ready means of tilting the oven at different angles, so that the transparent side thereof may be placed exactly at right angles to the direction of the solar rays. The interior of the oven as regards the arrangement for retaining the heat is of the same general construction as in the form of invention already shown; but in order to prevent the tilting of the oven to different angles and yet at the same time maintain the shelves of the oven horizontally the baking-chamber proper, 9, is made cylindrical in form and is revolvable in a cylindrical casing 56, supported by stays 57 within the wall 12, the space between said casing 56 and wall 12 being an air-chamber. The baffle-plate 22 in this construction is now made of a curved form to conform to the general shape of the baking-chamber proper. The frying-plate 40 is now no longer supported upon the top of the oven, but is arranged at the end thereof opposite to the door, being supported at one end by a standard 60 and at the other end having a tubular extension 61, which fits snugly within a sleeve 62 and extending to the air-chamber 11 of the oven. Air is admitted from said air-chamber through the extension or pipe 61 to the chamber 63 below the frying-plate 40, said chamber 63 being packed on all sides, except the frying-plate, in a manner similar to the oven proper. A shutter 64, movable by a handle 65, serves to close or open the pipe 61 when desired. The end of the pipe 61 within the oven is secured to the baking-chamber proper by means of straps 66, and since the frying-plate and its chamber are held securely fixed in the pedestal 60 the result is that the baking-chamber proper will be retained in the same position notwithstanding any adjustment or tilting of the exterior portion of the oven, and thus the shelves of the oven will always be maintained horizontal.

I claim—

1. A solar cooker having a confined air-space, means for preventing the conduction of heat from said air-space, said air-space being open on one side to the solar rays, a second confined air-space, a longitudinal plate

for broiling or frying forming one side of the inclosure of said latter space, a conduit from the first space to the second, and a movable shutter for closing said conduit, substantially as described. 70

2. A solar cooker having a cooking-chamber, a confined air-space around said cooking-chamber, said air-space being open on one side to the solar rays, a second confined air-space, a longitudinal plate for broiling or frying forming one side of the inclosure of said latter space, a conduit from the first air-space to the second, and a movable shutter for closing said conduit, substantially as described. 75

3. A solar oven having its rear portion formed in an arc of a circle and having a circular bearing in which said rear portion is movably mounted, a cylindrical cooking-chamber 85 removably mounted in said oven, and a confined air-space around said cooking-chamber, said air-space being open on one side to the solar rays, substantially as described.

4. A solar oven having its rear portion 90 formed in an arc of a circle and having a circular bearing in which said rear portion is movably mounted, a cylindrical casing in said oven, a cylindrical cooking-chamber removably mounted in said casing, and a confined 95 air-space around said casing, said air-space being open on one side to the solar rays, substantially as described.

5. In a device of the character described, the combination of a cooker having a cooking-chamber, a confined air-space around said chamber, said air-space on one side being exposed to the solar rays, a standard in which said cooker is revolvably mounted, and a second chamber connected with the first chamber in the line of the axis of revolution of said first chamber; and means for closing the connection between the two chambers when desired, substantially as described. 100

6. The combination of a cooker having a 110 baking-chamber, an air-space around said chamber, a suitable packing around said air-space of non-conducting material, said air-space on one side being exposed to the solar rays and provided on said side with a sheet 115 of glass to prevent the escape of the heated air, a standard or pedestal on which said cooker is revolvably mounted, a second chamber arranged at the end of the first chamber and having a conduit connected therewith in 120 line with the axis of the revolution of the cooker, and suitable means for connecting said conduit with said baking-chamber, to maintain the latter stationary during the revolution of the cooker, substantially as described. 125

In witness whereof I have hereunto set my hand in the presence of two subscribing witnesses.

M. M. BAKER.
